US00D551815S

(12) **United States Design Patent** (10) Patent No.: **US D551,815 S**
Schroeter (45) Date of Patent: **** Sep. 25, 2007**

(54) **ROBOT VACUUM CLEANER WITH
LOADING STATION**

(75) Inventor: **Joerg Schroeter**, Groebenzell (DE)

(73) Assignee: **BSH Bosch und Siemens Hausgeraete
GmbH**, Munich (DE)

(**) Term: **14 Years**

(21) Appl. No.: **29/254,806**

(22) Filed: **Feb. 27, 2006**

(30) **Foreign Application Priority Data**

Aug. 29, 2005 (EM) 000400288

(51) LOC (8) Cl. **15-05**

(52) U.S. Cl. **D32/21**

(58) **Field of Classification Search** D32/21,
D32/23-25, 28, 31; 15/319-320, 327.1,
15/327.2, 327.6, 327.7, 358, 340.1; 901/1,
901/47; 700/245, 259; 318/568.12; 180/168,
180/169, 204, 274; 701/23

(57) **CLAIM**

The ornamental design for a robot vacuum cleaner with loading station, as shown and described.

DESCRIPTION

FIG. 1 is a perspective view of a robot vacuum cleaner with loading station showing my new design;

FIG. 2 is a right view thereof;

FIG. 3 is a left view thereof;

FIG. 4 is a front view thereof;

FIG. 5 is a rear view thereof;

FIG. 6 is a top view thereof; and,

FIG. 7 is a bottom view thereof.
